(57) CLAIM

The ornamental design for snuff pouches in a snuff box, as shown and described.

DESCRIPTION

FIG. 1 is a top, back and side perspective view of snuff pouches in a snuff box embodying my new design.

FIG. 2 is a top view thereof.

FIG. 3 is a first side view thereof.

FIG. 4 is a second side view thereof.

FIG. 5 is a back view thereof; and,

FIG. 6 is a front view thereof.

Broken lines are used to illustrate features of the snuff box which form no part of the claimed design.

1 Claim, 4 Drawing Sheets(56)
